UNITED STATES PATENT OFFICE.

ALBERT BROWN, OF MENDOCINO, CALIFORNIA.

PAPER-BAG HOLDER.

SPECIFICATION forming part of Letters Patent No. 291,489, dated January 8, 1884.

Application filed October 30, 1883. (No model.)

To all whom it may concern:

Be it known that I, ALBERT BROWN, a citizen of the United States, residing at Mendocino, in the county of Mendocino and State of California, have invented a new and useful Paper-Bag Holder, of which the following is a specification, reference being had to the accompanying drawings.

This invention relates to paper-bag holders; and it has for its object to produce a device which shall be simple, convenient, inexpensive, and capacious, and which shall, in addition, be provided with accommodation for one or more balls of twine.

The invention consists in the improved construction and arrangement of parts, which will be hereinafter fully described, and particularly pointed out in the claims.

In the drawings hereto annexed, Figure 1 is a perspective view of my improved paper-bag holder. Fig. 2 is a longitudinal vertical sectional view of the same. Fig. 3 is a vertical transverse sectional view, and Fig. 4 is a detail view.

The same letters refer to the same parts in all the figures.

A A in the drawings designate the sides of my improved paper-bag holder, which are semicircular in shape, and connected by the bottom B, and by a vertical center piece, C, to which the said sides are secured by means of screws or other suitable fastenings. The sides A A are provided with inclined grooves D D to receive the inclined shelves E E, which are held detachably in the said grooves, and which serve to hold the bags, the larger bags being accommodated upon the lower shelves and the smaller bags upon the upper ones. Of the smallest bags, two sizes may be placed upon one shelf. The shelves being all inclined toward the center of the sides, the bags will be held safely in position. The inner ends of the shelves may be provided with pins or prongs F, which serve to hold the bags with additional security, and will prevent more than the bag which is laid hold of from being withdrawn at a time. The shelves being detachable, as stated, will enable the bags to be easily adjusted upon such pins or prongs when used; but the said pins or prongs may be dispensed with without departing from the spirit of my invention. The top shelves, G G, form

a trough, as shown, in which partitions H H are placed, which reserve the central portion of said trough for the smallest size of bags. 55 The end compartments, I I, of said trough are provided with cross-strips J, having perforations K, through which may pass the ends of balls of twine L, which may be placed in the said compartments, where they are held safely 60 and conveniently.

From the foregoing description, taken in connection with the drawings hereto annexed, the operation and advantages of this invention will be readily understood.

The construction is simple and inexpensive, and such that the device may be readily "knocked down" for shipment. The general appearance is attractive, and the arrangement of the bags is such that all the different sizes 70 are ready at hand and accessible. The twine-holding arrangement is also simple and convenient, and does not add to the cost of the device.

I claim as my invention and desire to secure 75 by Letters Patent of the United States—

1. As an improvement in paper-bag holders, the combination of a pair of semicircular sides having inclined grooves, a bottom and a vertical center piece connecting the said sides, 80 and inclined shelves held detachably in the grooves of the said sides, substantially as set forth.

2. The combination, in a paper-bag holder, of the semicircular sides having inclined 85 grooves, the bottom and a vertical center piece connecting the said sides, the shelves, and the top shelves connected so as to form a trough having partitions, as shown, forming separate compartments, the end compartments being 90 provided with perforated cross-strips, as and for the purpose set forth.

3. In a paper-bag holder, the combination, with the sides, of detachable shelves, the inner ends of which are provided with upwardly-projecting points or prongs, substantially as 95 and for the purpose set forth.

In testimony that I claim the foregoing as my own I have hereto affixed my signature in presence of two witnesses.

ALBERT BROWN.

Witnesses:

EUGENE BROWN,
A. D. McGIBBON.
